PRINTING MACHINE

Clayton E. Wyrick, Wyandotte, Mich.

Original application August 29, 1936, Serial No.
98,514. Divided and this application January
11, 1938, Serial No. 184,451

23 Claims. (Cl. 101—340)

This invention relates to printing machines and particularly to such machines for printing of forms or designs on one or more sheets, strips or webs of paper or other, like, printable material.

It is an object of this invention to provide a machine in which one or a plurality of strips, sheets or webs may be simultaneously fed and printed.

It is a further object of this invention to provide, in such a machine, a base unit having one or more printing units superposed thereon and pivotally connected thereto, whereby they may be swung upwardly on the base unit in order to afford free access to the parts of the respective units.

It is a further object of this invention to provide such a machine comprising a base unit with superposed, pivotally attached printing units, each equipped with printing plate means, ink supply means, and reciprocable carrier means, operative in each cycle, simultaneously to feed a web out of contact with the printing plate means, while transferring from the ink supply means to the printing plate means a predetermined amount of ink, while the carrier is traveling in one direction and operative, thereafter, while traveling in the opposite direction in its operative cycle progressively to engage the paper web (then held stationary against feeding movement) with the inked printing plate for the application to the web of a printed impression from the printing plate.

It is a further object of this invention to provide, in such a machine, means comprising a drive train so situated and located in the respective units as to be undisturbed by the operation of swinging of one or more of the respective printing units upwardly with respect to the supporting structure, whereby to gain full view and access to parts of the units.

It is a further object of this invention to provide, in the printing chamber of each unit, reciprocating means in the form of a carrier which, during its reciprocation, cooperates with mechanisms mounted in stationary manner to perform the various functions necessary to clamp the web in the unit in a stationary manner, to release the web, to advance the web, to again clamp the web, to bring the web progressively into contact with a printing plate, to print a form thereon and which, while feeding, transfers ink from an ink supply means to the surface of the printing plate.

It is a further object of this invention to provide such a machine having therein automatic means for feeding one or a plurality of sheets,

strips or webs through the machine in consecutive, predetermined lengths and means whereby the web may be processed or printed as it travels through the machine.

It is a further object of this invention to provide such a machine in which the web measuring mechanism, ink transfer means and impression roller means are mounted in a common carrier assembly adapted for reciprocatory movement with respect to a stationary printing type or form plate at predetermined speed to insure smooth action in inking the type, feeding the web, and printing the web.

It is a further object of this invention to provide a sequence of operations in the printing of forms upon webs comprising engaging the web and moving it forwardly a predetermined amount, while simultaneously inking a type plate supported therebeneath, releasing the web and pressing the web against the inked type plate by applying pressure thereto, progressively in a direction opposite to the direction of feed, and applying the pressure to the side of the paper opposite, or remote from, the inked type plate.

It is a further object of this invention to provide means for securing the web in a predetermined stationary position while making an impression thereon and to provide also means for automatically releasing the holding means at the end of each printing cycle and prior to the beginning of the feeding stroke.

It is a further object of this invention to provide means for securing the web in a predetermined stationary position while making an impression thereon and to provide also means for automatically releasing the holding means at the end of each printing cycle and prior to the beginning of the feeding stroke.

It is a further object of this invention to provide in each unit, means for feeding the web, or webs, means for transferring ink from ink fountains to the printing plates, and means for pressing the webs against the respective plates during the printing cycle.

It is a further object of this invention to provide ink fountain means adapted to deliver a predetermined amount of ink to the ink transferring means during each cycle of operation.

It is a further object of this invention to provide means for adjusting the quantity of ink supplied to the ink transferring means during each printing operation in a predetermined manner.

It is a further object of this invention to provide such means by which the application of ink

to each of the ink transferring means in the respective units may be adjusted, or totally prevented, in a predetermined manner whereby to compensate for the use of inks of varying characteristics in the respective units and/or for the purpose of providing means whereby any one or more of the superposed webs passing through the machine may remain unprinted, or be more lightly printed than the other webs simultaneously traveling through the machine and/or whereby the impressions simultaneously applied to the respective webs may be made uniform as to lightness.

These and other objects and advantages will appear from the following description taken in connection with the drawings.

This application is a division of my application Serial No. 98,514, filed August 29, 1936.

In the drawings:

Figure 1 is a side elevational view of a printing machine constructed according to the principles of my invention with a part of the supporting structure omitted;

Figure 2 is an end elevational view of the machine, as seen from the left of Figure 1;

Figure 3 is a similar end elevational view of the machine, as seen from the right of Figure 1;

Figure 4 is an end elevational view, in section, of the machine taken along the line 4-4 of Figure 1;

Figure 5 is a top plan view of the base frame of the machine with the printing frames and power connections therefor omitted for the sake of clearness of disclosure;

Figure 6 is a top plan view of one of the printing sections of the machine, the other printing sections being omitted in the interest of clearness;

Figure 7 is a diagrammatic view showing the cooperative relation of the carrier assemblies and other associated parts of the printing units, in the rearward position of the carrier;

Figure 8 is a view similar to Figure 7, but showing the carrier partially advanced in its forward or feeding and inking stroke;

Figure 9 is a view similar to Figures 7 and 8, but showing the carrier in its foremost position, at the end of its forward stroke or traverse;

Figure 10 is a side elevational view, in section, of the machine taken along the line 10-10 of Figure 6, with the parts in the position between that shown in Figure 9 and that shown in Figure 7, the direction of travel of the carrier being rearwardly;

Figure 11 is a top perspective view showing the details of the carrier assembly;

Figure 12 is a diagrammatic view, in end elevation, of the carrier assembly, as seen from the left side of the machine, showing the cooperation of parts to unclasp the web in the carrier, certain of the parts being broken away in the interest of clearness;

Figure 13 is a view, in perspective, partly broken away, of the construction of the ink transfer rollers and supporting frame of the carrier illustrated in Figures 11 and 12;

Figure 14 is a top plan view of the structure shown in Figures 11, 12 and 13; and

Figure 15 is a perspective view of the structure shown in Figure 1, with the printing units swung upwardly into elevated position above the base unit, details of a portion of the operative structure having been omitted in the interest of clearness.

Referring to the drawings in detail and with

reference particularly to Figures 1, 2, 3 and 15, I have shown, as illustrative of my invention, a machine comprising a base frame generally designated 1, which is mounted on a table 2 supported on legs 3 which have the shelf 4 rigidly secured therebetween. The drive motor 5 is rigidly secured to the under side of the table 2. Any other suitable source of power may be supplied, if desired.

10 The base frame 1 contains the aligning chamber and supports a type plate, an ink fountain assembly and three printing unit assemblies generally designated 6, the lower of which is pivotally secured at the rear end of the base frame 1 in a manner which will be hereinafter clearly described. The printing units, or printing unit assemblies, are identical, save for the fact that the first or lower printing unit only is equipped with a master print control for controlling the printing operations of the superposed printing units, and also an overload release drive clutch for operatively connecting to, and disconnecting from, the drive motor 5, the printing unit driving means. The base frame comprises a pair of longitudinal side plates 7 having a horizontally disposed plate member 8 disposed therebetween, and to the longitudinal sides of which they are secured by means of screws 9.

Disposed between the side plates 7, spaced from and parallel with respect to the plate member 8, is an aligner supporting plate 10 (Fig. 4) which, in conjunction with the side plates 7 and plate member 8, form the aligning chamber. The aligning means, the details of which are not shown, comprises an aligning frame which is slidable with respect to the aligning chamber and which is provided with suitably spaced rolls over which the respective webs 11 travel from their fanfolded position on the shelf 4 to the respective printing units.

The rolls supported in the aligning frame, which include the brackets 12, comprise an equal number of forward web guide rolls 13a (Fig. 10) disposed forwardly with respect to the aligning frame, and also rearward web guide rolls, designated 13. Switch means 13b is provided in association with the forward web guide rolls in the aligning frame, which become operative immediately upon the passage thereover of a torn place in a web, or upon exhaustion of a web, to energize the solenoid 14 which controls simultaneous opening of the operative circuit of the drive motor 5 and opening of the overload release clutch in the driving gear train under the control of hook means 11 disposed on a power transmission link member of the lower reciprocating carrier assembly.

In other words, when the webs passing through the aligning chamber are continuous, the control switch for the motor 5 is in such position as to close the operating circuit therefor, and the operative gear train is closed for reciprocation of the carrier assemblies through rotation of the motor 5. This means is fully described in my co-pending application Serial No. 98,514, filed August 29, 1936, of which this application is a division.

This means includes the solenoid armature 15 which is secured to the latch lever 16 and the lever mechanism 17 which is pivoted also to a side rail 1 and which has a notch cooperating with an end of the pivoted lever 18 in such manner that the lever 18 may be engaged with the notch of the lever mechanism 17 and retained against counterclockwise rotation upon its pivot by the

latching engagement of the lever 16 with the lever mechanism 17. When the lever mechanism 17 is so locked, the upper end of a portion of the mechanism is disposed below the operative path of the above-described hook means 71 in such manner that reciprocation of the carriers may take place without interference with the latched mechanism of the lever mechanism 17 by the above-described hook means 71.

When, however, the solenoid 14 is energized, as described above, the solenoid armature 15 is drawn rearwardly, or to the left, as seen in Figure 1, to the position therein shown whereby to release the lever mechanism 17 for extension under the influence of the tension spring thereof, into the operative path of the above-mentioned hook means 71 on the carrier reciprocating link 70. After the lever 16 has been thus released from the lever mechanism 17, the hook means 71 will engage the upper, extended end of the lever mechanism 17 and swing it in counterclockwise direction to release the lever 18 from the notch therein. The lever 18 has pivotally secured thereto the link 19 which is spring urged forwardly, or to the right, as seen in Figure 1, in such manner that immediately following movement of the lever mechanism 17 under the influence of the hook means 71, the link 19 is spring thrust forwardly, or to the right, as seen in Figure 1, to the position therein illustrated. The link 19 has thereon a switch operating plate 20 with a pair of projections 21 which are disposed forwardly and rearwardly of the motor circuit control tumbler switch lever 22.

In the position illustrated in Figure 1, the switch is in position to open the motor circuit but, when the link 19 is in its rearmost position, the position of the lever 22 is such as to close the operating circuit to make the motor 5 operative. The forward end of the link 19 is pivotally connected to a lever 23 which is rigidly secured upon a rotatable supporting shaft 24, Figure 4, which provides common support for the lever 25 having a clutch operating roller 26 rotatable thereon.

The power drive means of the base unit 1 comprises the pulley 28 connected by the belt 27 with the drive pulley of the motor 5, which pulley 28 is rigidly secured to the shaft 29. The shaft 29 is supported at one end in the bracket means 7a which is a downward extension of a side rail 7 and which has associated therewith the bracket plate 30. The opposite end portion of the shaft 29, adjacent the pulley 28, is supported by the bracket 31 which is secured by means of the bolt 32 to the under side of the plate 8.

Between the brackets 30 and 31, the shaft 29 has rigidly secured thereto a gear 33 at one side of which is the spacing collar 34 and at the other side of which is the spacing collar 35. The gear 33 meshes with a gear 36 rigidly secured to a gear 37 having common support therewith on the shaft 24, which shaft has the lever 23 and the clutch roller supporting lever 25 rigidly secured thereto, as described above. The gear 37 meshes with a gear 38 which is supported for free rotation on the stationary stud 39 affixed to a boss in the side rail or plate 7, and this gear 38 meshes with a gear 40 which is rotatably supported on the extended sleeve portion of a gear 41. The gear 41 is supported for free rotation by the shaft 42 which, in addition to its other functions, provides pivotal connection between the base unit 1 and the first superposed printing unit 6, as will hereinafter more clearly appear.

The shaft 42 has suitable cap screws provided

5 at each end which, in association with roller bearing means provided in the bosses of the base unit frame, render this shaft 42 freely rotatable in the base frame. The gear 40 has a sleeve portion 44 disposed toward the center of the frame and this is tapered to form a surface complementary to the inclined side surface of the clutch roller 26.

10 The righthand or central end of the gear 40 is provided with suitable apertures which receive complementary pins 45 of the sleeve member 46 which has its left end (Fig. 4) provided with an inclined or tapered surface similar to the tapered surface of the gear 40 and which is likewise complementary to the inclined side surface of the grooved clutch roller 26. This (left) end of the sleeve 46 is supported on the thrust bushing 47 which is freely rotatable on the shaft 42 and which has abutting engagement with the end of the gear 40 in such manner that, when the bushing 47 is resiliently thrust leftwardly, it forces the gears 40 and 41 together against the friction washer 43 in such manner that rotation of the gear 40 will be transmitted to the gear 41.

15 The sleeve 46 is provided with a central cylindrical bore 48 which receives a compression spring 49 having its left end in abutting engagement with the right end of the bushing 47 and its right end in engagement with an annular flange 50 on the sleeve 46. This spring 49 normally tends to expand the bushing 47 with respect to the sleeve 46. At its right end (Fig. 4), the sleeve 46 is provided with a cup-shaped annular flange which is adapted to engage a complementary thrust washer 51 disposed between the flange and a frusto-conical left end surface of the member 52 which is rigidly secured by means of the set screw 53 to the shaft 42.

20 Normally, when the clutch roller 26 is out of engagement with the complementary surfaces of the sleeve 46 and gear 40, the expansion of the bushing 47 with respect to the sleeve 46 causes the gears 40 and 41 to be thrust together with the thrust washer 43 therebetween, and also causes the cup-shaped righthand surface of the sleeve 46 to be thrust toward the frusto-conical surface of the member 52 with the thrust washer 51 therebetween in such manner that rotation transmitted to the gear 40 through the gear 33 will be likewise transmitted to the gear 41, the sleeve 46, the member 52 and the shaft 42. When, however, the clutch roller 26 is engaged with the tapered adjacent end surfaces of the gear 40 and sleeve 46, the gear 40 and sleeve 46 are moved together sufficiently to release the friction on the friction washer 43 and the friction washer 51 to cause the clutch to be opened. Furthermore, when the clutch 25 is closed, obstruction of the gearing will cause the clutch to slip and thus prevent damaging the parts in the printing frames thereabove.

25 The frames of the printing units 6 comprise the side plates 54 cut away along their central extent to form a trackway 55 for a purpose which will hereinafter appear. At each end portion, the side plates 54 are provided, at their upper end, with inwardly directed substantially horizontal flanges 56, to which are rigidly secured the roof plates 57 which divide each printing unit frame into two chambers. Rigidly attached to the longitudinal side edges of each roof plate 57, at the upper side thereof, by means of screws 59, are upper side plates 60. 30 Each pair of upper side plates 60 cooperates with

the supporting roof plate 57 to form the chamber of the printing unit which supports the type plate and ink fountain means. Aligned apertures are provided in the rear portion of each upper side plate 60 and each corresponding lower side plate 54 for receiving pintle means 61 for pivotally securing to each pair of upper side plates 60, the lower side plates 54 of the printing unit frame superposed thereon. The lower side plates 54 of the lower printing unit frame are secured to the side plates 7 of the base frame by means of similar pintle members 61 which are provided with a suitable bore for receiving the rotatable shaft 42, above described. A continuous transverse bar 61a is disposed in the apertures of the upper side plates 60 of the uppermost printing unit frame for a purpose which will hereinafter more clearly appear.

As shown in Figure 4, the lower side plates 54 of each printing unit are disposed inwardly, in close engagement, with the upper side plates 60 of the printing unit superposed directly therebelow, and the same is true of the cooperation of the lower side plates 54 of the lowermost printing unit with the side plates 7 of the base frame.

As shown in Figures 1 and 15, latch lever means 62 are pivotally supported adjacent the rear end of each lower side plate 54 for engagement with suitable stud means on the side plate disposed adjacent and therebelow, and these latch lever means 62 are constantly biased toward clockwise latching engagement by suitable tension springs connected therewith and with the supporting lower side plate 54. Each printing unit 6 may be moved pivotally upwardly about its pintle means 61 by manually releasing the latch lever means 62, as shown in Figure 15.

The carrier reciprocating means for each printing unit includes a pair of sprocket chains 63, each supported on the outside of each lower side plate 54, as shown in Figures 1 and 4. The supporting means comprises the rear chain supporting sprockets 64 supported for adjustment longitudinally of the supporting side plate and the forward chain driving and supporting sprockets 65, each pair of which is rigidly secured to a chain sprocket drive shaft 66 which is rotatably supported at either end in the corresponding lower side plate 54, as shown in Figure 4. The lowermost shaft 66 is driven through the gear 67 which meshes with the above-described gear 41, and this shaft also carries at its opposite end a gear 68 which meshes with a gear 69 rotatably supported in a slot provided in the roof plate 57 of the printing unit thereabove, as also shown in Figure 4. Each shaft 66 in the above printing units is likewise provided with a gear 68 meshing with a corresponding gear 69 supported by the roof plate 57 thereabove.

By the above described means, rotation of the gear 41, as above described, will cause the shafts 66 to rotate simultaneously at the same speed and this in turn will cause travel of each pair of chains on each printing frame also at the same speed. This travel of the chains 63 is translated into reciprocation of the respective carrier assemblies in each printing unit by the link members 70 which have their forward ends pivotally secured to a pintle of each chain 63, as shown in Figure 1, and which have their opposite, or rear, ends pivotally secured to the carrier assemblies, as will be hereinafter more clearly described. The righthand link member

70 on the lowermost printing unit has the hook member 71 formed thereon, which cooperates, as above described, in cooperation with the lever mechanism 17, to cause simultaneous opening 5 of the clutch in the drive gear train through clutch roller 26 and opening of the power circuit of the motor 5.

For supporting or suspending the webs in the respective printing units, a rotatable rear supporting roller 72 is disposed between the lower side plates 54 of each unit adjacent the rear thereof, as shown in Figure 2. Also, secured to each shaft 66 for axial adjustment therewith and for rotation therewith are web driving rollers 15 73 which are adapted for intermittent driving engagement with the webs, during the operative cycle of the machine, as will be hereinafter more clearly described.

Clamping means is also provided for maintaining the webs in stationary relation, and this means comprises the resiliently faced clamping members 74 which cooperate with the surfaces of the rear rollers 72 to clamp the web at the rear of the unit and also resiliently faced forward end clamping means 75 which are adapted for intermittent supporting engagement with the under side of the web in the forward portion of the unit to lift the web from engagement with the web driving rollers 73, as will hereinafter more clearly appear.

The manner of supporting the clamping or brake means 74 and 75 is as follows. Pivotally supported between the lower side plates 54 of each unit forwardly of the roller 72 is a clamping member support rod 76 upon which the arm portions of the clamp members 74 are rigidly secured. The members 74 are normally biased toward engagement with the rollers 72 by the spring means 77 disposed between the means 74 and the roof plates 57, as shown in Figure 10. Secured to the righthand end of each support rod 76, outside the frame, is a lever arm 78 to which is pivotally attached a link 79 which extends forwardly and which has pivotally secured at its forward end the lever arm 80 which is rigidly secured to a rod 81 which is similar to the rod 76 and similarly disposed between the lower side plates 54 of each unit.

Also rigidly secured to the rod 81, at their rear ends is a pair of clamp member support arms 82 which have rigidly secured, at either end, to their forward end portions, the cross bar 83 upon which the clamp members 75 are directly mounted for transverse adjustment thereon. The clamp member support arms 82 are constantly resiliently urged upwardly, or in counterclockwise direction about the rods 81 by tension springs secured at one end thereto and at the other end to the roof plate 57 thereabove.

Means is provided for resiliently pressing the web downwardly against the clamp member 75 and/or the web driver rollers 73 which comprises a pair of arms 84 which are pivotally mounted, at their rear ends, on the shaft 81 between the clamp member support arms 82 and which have rotatably supported at their forward ends the web compression roller 85.

A flat leaf spring member 86 is secured at each end to one of the arms 84 between the web compression roller 85 and the rod 81. This leaf spring member 86 has a block rigidly secured to its mid-portion which is engaged by the lower end of an adjusting screw 87 screw-threaded in the roof plate 57. By means of this arrangement, the downward resilient pressure exerted by the web

compression roller 85 upon the web may be adjusted by means of the screw 87, and this adjustment, along with the resiliency in the facing provided on the clamp members 75 and the inherent resiliency of the material from which these clamp members are formed, permits of very close adjustment of the pressure exerted on the web between the compression roller 85 and the cooperating clamp members 75.

Due to the rigid connection of the lever arm 78 with the rod 76 which supports the clamp or brake member 74 and the rigid connection of the lever arm 80 with the rod 81 to which is rigidly secured the clamp member supporting arms 82, and the positive location of the lever arms 78 and 80 by the connecting link 79 when the link 79 is thrust to its rearmost position, as shown in Figures 7, 9 and 10, the clamp or brake members 74 tightly engage the web with the supporting roller 72, while the supporting clamp members 75 urge the web upwardly against the downward force of the web compression roller 85 in such manner as to prevent the transmission of movement thereto from the web driver rollers 73.

Likewise, when the link 79 is thrust forwardly, the clamping members 74 are moved upwardly from clamping engagement with the web, while the supporting clamp members 75 are moved downwardly to permit the web compression roller 85 to resiliently press the web against the web driving rollers 73 for feeding the forward supported portion of the web through the printing unit. The rearmost position of the link 79 which defines the clamping position of the clamping members 74 and 75 may be adjusted by means of the set screws 88 provided for that purpose and rigidly supported on the right upper side plate 60 of each printing unit.

As above explained, the lower side plates 54 of the frames of the printing units 6 are cut away along their central extent to form a trackway 55. This trackway (Fig. 10) is provided with suitable side plate means for retaining on the trackways the roller means which support the carrier units for reciprocation on the trackways 55.

The carrier assemblies (Figs. 7 to 14) are each of substantially identical construction, save for slight differences in the equipment of the carrier assembly of the lower unit. Each of the carrier units is provided with a frame including a pair of plate-like side members 89 which are secured in rigid spaced relation by means of the L-section plate member 90 attached at the rear upper corners of each side member 89 and also the arcuate paper guide plate 91 arranged centrally between the two side members and rigidly attached at each end thereto.

Also rigidly locked at each end to the respective side members 89 by means of set screws 93 is the front axle member 92. This axle member 92 has rotatably secured on its end portions disposed outside the side members 89 the ball bearing supporting rollers 94 which roll in the trackway 55 and thus support the forward end of the carrier unit for reciprocation in the corresponding trackway. The rear end of each carrier is supported on the trackway 55 by means of similar ball bearing supporting rollers 95 which are rotatably supported on the rear axle member 96. This rear axle member 96 is rotatably journaled in the side members 89 and is adapted to have secured to each end thereof the rear end portion of the corresponding pair of the link members 70, as shown in Figure 14.

In this manner, the rear axle member 96 pro-

vides pivotal connection between the carrier frame and the link members 70 in such manner that travel of the sprocket chains 63 will cause reciprocation of the carrier assemblies in the trackways 55 in such manner that, when the forward ends of the link members 70 are traveling through the straight reaches of the sprocket chains 63, the carrier assembly is reciprocated at constant speed, while the speed of travel thereof is reduced when the connections of the link members travel through the curved portions of the chain path where the sprocket chain extends about the supporting chain sprockets 65. In such manner, the carrier assemblies are simultaneously given reciprocation in their trackways. The reciprocating movement is, in effect, modified simple harmonic motion.

Journalized for free rotation in the front portion of the side members 89 and disposed below the front axle member 92 is a web supporting shaft 97 having an axial slot 98 disposed therein. Supported for axial adjustment on the web supporting shaft 97 is a plurality of web support rollers 99 having serrated end flanges 100 adapted to supportingly engage fresh printed portions of a web without smearing. Each of the web support rollers 99 is provided with a spring member 101 which engages the axial slot 97 in the web support shaft 98 to secure the rollers 99 thereon against relative rotation with respect thereto.

Also supported on the shaft 98 is a pair of edge support rollers 102 which are secured to the shaft 98 in the same manner as are the rollers 99. These edge support rollers 102 are provided with a cylindrical surface for engagement with the side portions of a supported web. Each of the side members 89 is provided adjacent the forward portion of its lower edge with apertures 103 which provide clearance for swinging movement of the impression roller 104 which is suitably pivotally attached at each end to one of the impression roller support arms 105 which are pivotally secured at their rear ends by means of pivot screws 106 to the outside of the side members 89 rearwardly of the apertures 103. The impression roller support arms are capable of swinging movement about their pivot screws 106 for the purpose of advancing the impression roller 104 downwardly in such position that it may resiliently press a web against the inked printing plate of the printing unit during the rearward stroke of the carrier and upwardly to retracted position wherein it is substantially spaced upwardly from the printing plate during the forward, or feeding, stroke of the carrier.

Each roller support arm is provided adjacent its forward and upper edge with a notch adapted for engagement with a flanged roller 107 having the flange 108 thereof retained in an undercut slot or groove 109 in each side member 89 of the carrier. The roller 107 is rotatably secured to a flange 111 of the shifting lever 110 which is provided at its upper end with an elongated slot which is supported on the stud 112 which has an elongated head 113 disposed outwardly of its supporting side member 89, which head is provided with a transverse bore through which extends the screw-threaded screw member 114 having the nut 115 at its upper end to control its movement downwardly with respect to the head 113 of the stud 112.

A compression spring 116 surrounds the lower end portion of the screw 114 and has one end thereof in engagement with the under side of the head 113 and the other end in engagement

with the spring thrust adjusting block 117 which is screw-threaded on the screw 114. The shifting arm 110 has thereon a projection to which is connected one end of a tension spring 118 which has the other end thereof secured to a projection provided on the extreme end of the impression roller support arm 105, as shown in Figure 12. The cooperation of the parts is such that, when the shifting arm 110 is moved to its extreme clockwise position, the impression roller 104 is extended downwardly into printing position, while, when the shifting arm 110 is disposed in its extreme counterclockwise position, the impression roller 104 is sufficiently spaced from the type or printing plate to prevent engagement of the web therewith. The details of this structure are more clearly described in my copending application Serial No. 98,514, filed August 29, 1936.

The means for actuating the shifting arms comprise print control levers 119 which are suitably supported for manual adjustment into and out of the operative path of the shifting arms or levers 110 for cooperation therewith, as shown in Figure 9, to shift the impression roller 104 downwardly into printing position. A master print control is provided on the lowermost printing unit 6 and has operative connection by means of pins 119a with the printing control arms of the other superposed printing units. By releasing the latch member 120 from latching engagement with the lever 121, the print control arms 119 of the lowermost unit may be permitted to move downwardly below the operative path of the shifting arm 110 in such manner that the shift arm or lever 110 will be undisturbed during reciprocation of the carrier. In this manner, reciprocation of the carrier may occur without effecting shifting of impression roller 104 to printing position, whereby web feeding may occur without web printing.

Adjustably secured on the top surface of the plate member 90 by means of a pair of slots which cooperate with screws 123 is the web support plate 122 which has its forward edge inclined upwardly for engagement with creases in the fanfolded webs for predeterminedly locating the webs with respect to the carrier. As shown particularly in Figures 7 to 10, the web, in its path through the printing units, passes between the roller 72 and the cooperating clamping or brake means 74, over the web supporting plate 122 and the arcuate paper guide plate 91 and thence beneath the impression roller 104 and over the web support rollers 99, whence it passes between the web compression roller 85 and the cooperating clamp member 75.

As above explained, by controlling the position of the clamp members 75, the web is intermittently placed into contact with the web driving rollers 73 by the web compression rollers 85. The means for controlling the operation of the clamping means includes a substantially square block member 124 which is fixed to a link 79 and which is adapted to cooperate with notch means 126 provided in the clamp locking cam 125 which is pivotally supported on the screw 127 which is fixed to the side frame of a unit. The clamp locking cam 125 is biased in clockwise direction by the tension spring 128 which is secured at one end to the clamp locking cam 125 and at the other end to the link 79. Normally, therefore, when the block 124 is disposed sufficiently forwardly, the clamp locking cam 125 will have the

notch means 126 thereof engaged therewith to prevent rearward movement of the link 79.

Likewise, due to the fact that the clamp member support arms 82 are resiliently urged upwardly, when the clamp locking cam 125 is moved upwardly to permit the block 124 to move rearwardly of the notch means 126, the link 79 will be thrust rearwardly for clamping. This movement of the clamp locking cam 125 upwardly for the above-described purpose, is accomplished by engagement with the lower downwardly inclined edge thereof of the adjustable screw 129 which is secured transversely in screw-threaded relation at the righthand end of the front axle member 92, as shown in Figure 9. This occurs when the carrier has substantially completed its forward travel in the printing unit. The clamping means are then applied to maintain the web stationary until, after the carrier has moved rearwardly or to the left, as shown in Figure 8, and thereafter moved rightwardly a predetermined amount, the link 79 is again thrust rightwardly for engagement of the block 124 in the notch means 126 of the clamp locking cam 125.

The means for determining when this unclamping shall occur comprises a thrust block 130 adjustably, clampingly secured to the link 79 by means of the screw 131 and also a second adjustable block 132 which is adjustably secured to the stationary bar 133 on the frame. The block 132 is adjustable on the bar 133 by means of the screw 134 which corresponds to the screw 131 in the thrust block 130. Pivoted on the screw 134 is the cam lever 135 which has thereon a stud to which one end of the tension spring 136 is secured. The opposite end of the tension spring 136 is connected to a stud provided on the pawl member 137 which is pivoted on the screw 138 which is fixed in stationary manner to the block 132. The forward lower end of the cam lever 135 is adapted for abutting engagement with the block 130 which is adjustably, though fixedly secured to the link 79.

The righthand link 70 of each printing unit 45 is provided with a clamp operating roller 139 which, in the forward motion of the carrier, engages the cam lever 135 and forces it upwardly in counterclockwise direction against the thrust block 130 which is thus thrust forwardly (Fig. 8).

As the thrust block 130 is rigidly, though adjustably, secured to the link 79, the link 79 will be thrust forwardly, or to the right, to cause unclamping of the web 11 and, at the same time, the block 124 will be engaged in the notch means 126 of the clamp locking cam 125 to lock the clamping means out of operation, as shown in Figure 8. This permits the carrier, to which the web is then clasped, to advance the web forwardly while the forward end thereof is kept taut by the driving rollers 73 until the clamping means is operated by engagement of the screw 129 with the lower, downwardly inclined edge of the clamp locking cam 125 to release the block 124 from the notch means 126 and permit rearward movement of the link 79 (Fig. 9). The web is unclasped from the carrier substantially simultaneously in order that the carrier may move rearwardly without carrying the web therewith.

During this rearward movement of the carrier, the impression roller 104 is in its downward or printing position in order that it may resiliently press the web, progressively into engagement with the inked printing plate, hereinafter described. The means for clasping and unclasping the web to the carrier (Figs. 7 to 12 and 14)

comprises means cooperating with the web support plate 122 for this purpose.

As shown in Figure 11, the shaft 140 is rotatably supported between the side members 89 and extends outwardly beyond the lefthand side member 89, where it is provided with an arm 141 rigidly secured thereto. Also rigidly secured to the shaft 140 between the side members 89 is a pair of arms 142 which are provided at their free ends with supporting studs 143. Each stud 143 is adapted to removably support the forward end of one of the pair of roller supporting links 144 which are secured together in rigid spaced relationship by the brace rod 145 and which have rotatably secured between the free, or rear, ends thereof the clasping roller 146. The upper end of the arm 141 has one end of a link 147 pivotally secured thereto and the other end of the link 147 is pivotally secured to the pin 148. The pin 148 is rigidly secured to the upper end of the arm 149 which is rigidly secured to the bar 150 which has cylindrical end portions journaled in the side members 89. At its righthand end, the bar 150 is provided with a rigidly attached notched lever 151 which cooperates with the pawl 137 during the forward travel of the carrier, as hereinafter more clearly described.

As may be clearly seen by comparison of Figures 7 to 10 inclusive, the clasping roller 146 may be clampingly engaged with the web support plate 122 to clasp the web to the carrier by rocking the bar 150 rearwardly, or in counterclockwise direction, by engagement of the notched lever 151 with the pawl 137 during the forward movement of the carrier. As the pawl 137 is mounted on the adjustable block 132, the point in the travel of the carrier, at which the clasping will occur, may be predeterminedly adjusted, as may be desired. By means of this adjustment, the length of feed, or travel of the web when clasped with the carrier may be predeterminedly controlled.

As above described, the cooperation of the notched lever 151 with the pawl 137 effects clasping of the web to the carrier. The means for rocking the shaft 140 forwardly to remove the clasping roller 146 from clamping engagement with the web support plate 122 to release the web from the carrier comprises means cooperating with the pin 148 to rock the interconnected bar 150 and shaft 140 in clockwise direction, as seen in Figures 7 to 10 inclusive, and in counterclockwise direction, as seen in Figure 12. This means includes the pin retainer member 152 which is secured by means of screw 153 to the rigid boss on the lefthand link 70 of each printing unit (Figs. 4, 12 and 14).

This pin retainer member is formed of spring metal and has a hook-shaped forward portion. The disposition of the pin retainer member is such that, due to the inclination of the link 70 during forward feeding movement of the carrier, the pin 148 is resiliently supported thereon in such manner as to lock the clasping roller 146 in its clamping engagement with the web support plate 122 (after placed therein by cooperation of notched lever 151 with pawl 137) until it is removed therefrom. The means for removing it therefrom comprises the stationary pin hook member 154 which is suitably located on the unit frame. This pin hook member is disposed oppositely with respect to the pin retainer member 152 and is likewise formed of spring metal having a rearwardly and downwardly inclined hook at the end thereof.

The cooperation of this means is illustrated in Figure 12, wherein it will be seen that, when the carrier is moving forwardly in the direction of the arrow in that figure, the pin 148 is supported upon the pin retainer member 152. During the extreme portion of the forward travel of the carrier, the pin 148 will pass under the pin hook member 154. When the direction of travel of the carrier is reversed, as above described, the pin 148 will engage the pin hook member 154 and this pin hook member 154 will retard the pin 148 in such manner that the carrier will move rearwardly independently thereof in such manner as to cause the pin 148 to be drawn forwardly of the hook portion of the pin retainer member 152. The shaft 140 and bar 150 are thus swung forwardly to release the clasping roller 146 and thus the web is released from clamping engagement with the carrier in order that further rearward movement of the carrier may take place with the impression roller 104 in downward position, as above described, for progressively engaging the free web (which is clamped to the unit frame) with the inked printing plate for application to the web of a printed impression.

The manner in which the impression roller 104 is shifted downwardly is described above and the means for returning the impression roller 104 to its upward position, in preparation for the next forward, or feeding, stroke of the carrier, comprises stationary rollers 155 (Figs. 7, 8 and 9), which engage the shifting arms 110 for that purpose (Fig. 7).

It will thus be seen that the carrier mechanism includes means for clasping and unclasping the web to the carrier frame at predetermined adjustable points in the operative cycle and that means is also provided for cooperation with the carrier for predeterminedly clamping and unclamping the web in stationary manner in the printing unit. Thus, as shown particularly in Figures 7 to 10 inclusive, the carrier begins its forward movement with the web unclasped therefrom and clamped in stationary manner in the printing unit (Fig. 7). Thereafter, by substantial simultaneous engagement of clamp operating roller 139 with cam lever 135 and lever 151 with pawl 137 (Fig. 8), the web is unclamped from the frame of the printing unit and clasped to the forward moving carrier.

Simultaneously with unclamping of the web from the printing unit frame, the forward portion thereof is engaged with the web driving rollers 73. The forward motion of the carrier with the 55 clasped web continues until the web is unclasped from the carrier and clamped in stationary manner to the frame (Fig. 9).

As also shown in Figure 9, the impression roller 104 is shifted downwardly and during the rearward movement of the carrier, the web is progressively engaged with the printing plate by this impression roller 104. The parts then take the position shown in Figures 7 and 10, while the impression roller 104 is shifted upwardly, as shown in Figure 7, in preparation for the succeeding forward stroke of the carrier.

Rearwardly of the aperture 103 provided in each side member 89 is an aperture 156 which extends upwardly from the lower edge of each side member 89 and which provides means for accommodating an ink transfer assembly in the carrier. The ink transfer assembly (Figs. 7 to 14) comprises a frame 157 having rotatably mounted therein a pair of identical ink transfer rollers 158. These ink transfer rollers have their cen-

tral portions provided with suitable resilient clothing such as rubber, synthetic rubber or the like, and have collars 159 rigidly secured thereto at each end.

The pintles 160 of each of the ink transfer rollers are rotatably supported in sleeve members 161. These sleeve members are provided with inwardly disposed enlarged shoulder portions with flat sides adapted to be supported in upwardly directed slots 162 in the vertical side portions of the frame 157. The frame 157 is provided with two of these slots 162 in each vertical side portion thereof and each pair of slots spaced apart a suitable distance. The outer ends of the sleeve members 161 are provided with cylindrical exteriors and these cylindrical portions fit into suitably spaced apertures in the attaching plate 163 which is disposed thereover and drawn inwardly toward the vertical side portions of the frame 157 by means of bolts 164, each having its outer, or head, portion disposed in a sleeve member 165. By tightening the bolt 164, the attaching plate 163 may be drawn inwardly and the sleeve members 161 accordingly adjusted so as to properly adjust the amount of axial movement permitted on the part of the ink transfer rollers, as may be desired.

The top surface of the frame 157 is provided with a slot 166 extending from side to side thereof, which is adapted to accommodate, for reciprocation and rotation therein, a rigid ink spreader roller 168 having the pintle 169 thereof rotatably supported in suitable aperture means 167 provided in each side portion of the frame 157. Suitable grooved bushings are slidably and rotatably supported upon the pintle 169 at each end, and the grooves thereof are engaged by downwardly directed depressions 171 of the flat spring clamp members 170 which are each suitably located on and secured to the top surface of the frame 157 by screws 171a. By loosening the screws, the ink spreader roller may be released from the frame 157 (Figs. 13 and 14).

The lefthand end of the pintle 169 is provided with a rigidly attached grooved roller 172 which engages a vertically disposed, downwardly directed flange 173 of the horizontally disposed lever 175 which is pivoted by means of the screw 174 to the top surface of the left side member 89 (Figs. 11 and 12). The forward end of the lever 175 is provided with a rotatable roller 176 and a spring member 177 secured to the inner side of the lefthand side member 89 constantly resiliently urges the forward end of the lever 175 outwardly, or to the left of the carrier. The under side of each roof plate 57 is provided with a suitably located cam plate 178, Figure 14, which is constantly engaged by the roller 176 due to the resilient pressure applied thereto by the spring 177. Due to the inclination of the inwardly disposed edge of the cam plate 178, the lever 175 is swung laterally during reciprocation of the carrier to cause transverse reciprocation of the ink spreader roller 168. (See Fig. 14.)

As the ink spreader roller 168 directly engages the ink transfer rollers 158, the reciprocation thereof insures uniform distribution of ink on the surfaces of the ink transfer rollers 158. The frame 157 is removably secured in position in the carrier by means of a pair of spring clamps 179 which are rigidly secured to the plate member 90 of the carrier at their upper ends and which are provided with suitable projections at their lower ends which engage complementary projections in

the frame 157 to retain the frame 157 against displacement.

The ink transfer rollers 158 are constantly resiliently urged downwardly by downwardly sprung 5 pressed pins 180 which extend upwardly into suitable bores provided in the side members 89 and which are so disposed that their lower ends engage the sleeve members 161 which support the pintles 160 of the ink transfer rollers 158 (Figs. 11 and 12). The frame 157 of each carrier may 10 be removed therefrom by releasing the spring clamp members 179 and removing the frames downwardly from the carrier in order that replacement of the ink transfer units may be made 15 for convenience in changing the color of printing ink used in the respective printing units. It will thus be seen that the ink transfer units are 20 removable and comprise resiliently clothed ink transfer rollers and an associated ink spreader roller which is constantly reciprocated transversely during longitudinal reciprocating movement of the carrier in the printing unit.

The ink transfer assembly cooperates, during reciprocation of the carrier, with an ink fountain 25 assembly, generally designated 181, and a printing plate generally designated 182, which are both secured to each roof plate 57 in the second printing unit and the unit thereabove and to the plate 8 of the base frame in the lowermost printing unit (Figs. 2, 5 to 10 and 15).

The type plate structure and support means is 30 shown in Figures 5, 6, 9, 10 and also in Figure 15. As shown in Figures 5 and 6, the plate 8 of the base unit 1 and also each roof plate 57 of the 35 superposed printing units is provided with a pair of longitudinally extending type rails 183 which are disposed in parallelism with one another. The screw 185 extends through a slot 184 in the righthand type rail 183 and is screw-threadedly 40 secured in the side of the type base 186 for securing it adjustably between the type rails 183. The lock washer 185a is disposed between the head of the screw 185 and the side of the type rail 183 for locking purposes. By releasing the 45 screw 185, the type support 186 may be adjusted longitudinally between the type rails 183.

The type support 186 is provided with a plurality of parallel transverse slots 187 and also a plurality of longitudinally disposed undercut slots 188. The transverse slots 187 are adapted to receive a transverse flange of each of the members 189, each of which is connected by means of a tension spring 190 with a member 191 which is similar to the member 189 and which is adapted to engage the rearward edge of a type plate 192. The type plate 192 rests upon the top face of the type support 186 with its forward edge in engagement with an upstanding flange member 193 which is rigidly attached to the supporting plate 8, or 57, or formed integrally therewith.

The members 189 may be engaged in any desired one of the transverse grooves or slots 187 to accommodate type plates 192 of various lengths. The spring connection 190 between each member 189 and its corresponding member 191 makes 65 possible the insertion of the members 189 in the desired transverse groove or slot 187 in such manner that the members 191 apply resilient pressure to the rear edge of the printing plate 192 in such manner as to securely retain its forward transverse edge in snug abutment with the upstanding flange member 193.

The type plate, or printing plate 192 may be removed from the machine by merely drawing rearwardly the members 191 sufficiently to swing

the type plate upwardly about its forward transverse edge. For substitution of a different type plate, it is merely necessary to engage each member 191 with the rear transverse edge of the desired plate and move the plate rearwardly a sufficient distance, after which the forward end thereof is lowered into engagement with the upstanding flange member 192 (Fig. 10).

Disposed rearwardly of the type plate 192 and its supporting means is a transverse aperture provided in each plate 8 and each roof plate 57 and designated respectively 8a and 57a (Fig. 10). These apertures provide access to the ink fountain assemblies 181 mounted on the respective plates in a manner which will hereinafter more clearly appear. The details of the ink fountain assemblies are illustrated in Figures 5 to 10 inclusive and they are also shown in Figures 2 and 15.

A substantially L-shaped spring clamp member 194 is secured to the plate 8 and also to each roof plate 57 rearwardly of and adjacent the apertures 8a and 57a respectively, as shown in Figures 2, 5, 6 and 10. At its upper end, this spring clamp member 194 is provided with a substantially horizontal forwardly directed flange which is adapted for close engagement with the rear upper transverse edge of the ink fountain assembly and which cooperates with the rear ends of type rails 183, with which the forward wall of the ink fountain assembly abuts, to resiliently and removably secure the ink fountain assemblies 181 to the respective supporting plates 8 and 57 respectively in predetermined position with respect to the type plate assemblies 182, as shown particularly in Figure 10.

The ink fountain assemblies in all printing units are identical. The ink fountain assemblies comprise box-like ink containers with bottom and sides formed of one integral plate 195 and with ends formed of relatively thick plates 196. A cover plate 197 is suitably attached to the top of the container and is provided with a transverse aperture 198. Rotatably mounted in each container are three rolls designated 199, 200 and 201 respectively. The rolls 199 and 200 are rotatably secured in rearwardly extending flanges of a substantially U-shaped frame 202, which frame is resiliently urged rearwardly by means of springs 203 attached at the sides of the frame 202 in order to retain the roll 200 in close engagement with the roll 201.

The rolls 200 and 201 have elongated pintles at the left, which extend through the lefthand end plate 196 of the container. To the ends of these pintles are rigidly attached interengaging gears 200a and 201a, whereby, when the roll 201 is rotated in counterclockwise direction, as seen in Figure 10, the roll 200 is rotated therewith, but in clockwise direction as seen in that figure. The leftward extending pintle of the roll 200 is received in the slot in the lefthand plate 196, whereby the frame 202 and the supported rolls 199 and 200 may be removed bodily from the ink container. The top plate 197 is secured on the top of the ink container by means of the spring clamps 204.

As may be seen particularly in Figures 5 and 6, the pintle of the roll 201 extends also to the right and has rigidly secured thereto the ratchet member 205 and the rigidly attached handle portion 206. Rotatably mounted between the members 205 and 206 is a lever member 207 which carries a transversely disposed pin 208, upon which is pivotally mounted a click member 209 which is urged toward the teeth of the ratchet member

205 by means of the spring 210 (Fig. 5). At the lower end of the lever 207 is a short arm 211 which is adapted for cooperation with the adjusting screw 212 in a manner which will hereinafter more clearly appear.

Pivotedly secured to the righthand plate 196 for engagement with the teeth on the ratchet member 205 is the pawl 213 which has connection with the lever 207 by means of the tension spring 214. The adjusting screw 212 is screw-threadedly mounted in a block 215 which is secured by means of screws to the top surface of the supporting plate member 8, or 57, in such position as to align the adjusting screw 212 with the short lower arm 211 of the lever member 207. By adjustment of the adjusting screw 212 longitudinally in the block 215, the initial position of the lever 207 may be adjusted as desired. The carrier is provided with means cooperating with this lever 207 to effect rotary movement thereof through a predetermined degree of arc upon each reciprocation of the carrier. This means comprises a roller 216 which is rotatably supported at the rear lower corner at the righthand side member 89 of the corner.

As is shown most clearly in Figures 7 to 9, the roller 216 engages the upper end of the lever 207 at the end portion of the rearward stroke of the carrier, whereby the lever 207 is swung to the left, as seen in Figure 7, and the ink roll 201 is given an amount of counterclockwise rotary movement which depends entirely upon the adjusted or "at rest" position of the lever 207, which position may be predeterminedly controlled by adjustment of the adjusting screw 212, as above explained. Comparison of the positions of the lever 207 in "at rest" position (Fig. 8) with that of Figure 7, in which it is depressed, will indicate just how this rotation of the ink roll 201 occurs.

By longitudinal adjustment of the adjusting screw 212, the "at rest" position of the lever 207 may be predeterminedly adjusted, as desired, by changing the inclination of the lever 207. To increase the arc through which the lever 207 travels under the influence of the roller 216, the adjusting screw 212 is backed off or adjusted rearwardly with respect to the block 215, while adjustment of the screw 212 forwardly with respect to the block 215 will decrease the arc through which the lever 207 is advanced by contact with the rearwardly moving roller 216.

In this manner, the arc through which the ink supply roller 201 is advanced, upon each return stroke of the carrier, may be predeterminedly adjusted and, obviously, the amount of ink supplied from the receptacle to the surface of the roller 201 will vary directly with the extent of the arc through which the roller 201 is advanced. As the roller 201 is engaged by the ink transfer roller means 158 of the carrier upon each rearward stroke of the carrier subsequent to a printing operation, the amount of ink supplied to the ink transfer roller means 158 will be proportional, therefore, to the arc through which the lever 207 is swung.

After the printing of the web 11 has been accomplished during each cycle of operation, the rearmost roller 158 passes over the ink supply roller 201 in the ink fountain means, as shown in Figures 7 and 10. Thereafter, during forward travel of the carrier and the ink transfer rollers 158, the rearmost roller 158 transfers ink to the ink spreader roller 168, from whence it is supplied to the foremost ink transfer roller 158 and, due to the axial reciprocation of the ink spreader

roller 168, as above described, the spreading of the ink uniformly on the surfaces of the ink transfer rollers 158 continues even while the ink transfer rollers 158 are in engagement with the upper, or printing, surface of the printing plate 192.

During the engagement of the ink carrying, ink transfer rollers 158 with the printing surface of the printing plate 192, ink is transferred from the rollers 158 to the printing surface of the plate 192 during forward travel of the carrier. At that time, as above explained, the web 11 is unclamped from the printing unit frame and is clasped to the forward moving carrier and moved thereby out of contact with the printing plate 192, because of the upward disposition of the impression roller 104.

On the return, or printing, stroke of the carrier, when the web 11 is clamped in stationary manner independently of movement of the carrier, the ink transfer rollers 158 travel rearwardly in advance of the resiliently downwardly pressed plate engaging web surface. This engagement of the ink transfer rollers 158 provides additional insurance of uniformity of ink distribution on the printing surface of the printing plate 192 immediately before progressive engagement of the web 11 therewith by the resiliently downwardly urged impression roller 104.

The other operations occurring during each operative cycle of the printing units have been described above and it will thus be understood that, in the operation of the machine, the webs 11 travel through the aligning chamber and thence through the respective printing units where they are alternately clamped in stationary manner, and intermittently fed forwardly in predetermined feed lengths corresponding to the desired spacing between printed type forms thereon, and that, after each forward feeding movement of the web occurs (simultaneously with inking of the type plate 192), the web is unclasped from the carrier, clamped in stationary manner in the frame of the printing unit, and thereafter progressively engaged with the inked surface of the type or printing plate 192 by the impression roller 104 during rearward travel of the carrier in the printing unit.

As shown in Figure 15, interleaved, fan-folded webs 11 may be supported upon the shelf 4 of the machine frame and they may be separated prior to introduction to the aligning chamber by the separator means generally designated 217. This means includes a plurality of separator rods adapted for insertion between adjacent webs, as most clearly described in my copending application Serial No. 98,514, filed August 29, 1936. As is also most clearly described in that application, upon issuing from the respective printing units in superposed relation, the webs may pass through a web delivery guide generally designated 218 which includes certain shafts driven through belt means 218a from a printing unit for guiding the webs when issuing from the printing units in superposed relationship, while again bringing them together in the same relationship in which they are disposed when resting upon the shelf 4. Thereafter, the webs may be treated in any desirable manner, though they are preferably refolded into superposed fanfolded relationship by stacker means (not shown), which is operated from the lower unit of the machine by a linkage generally designated 219.

Certain other features of the machine, which are not, per se, a part of this invention, such as the counter means 220 and the master print

control means, are not described in this application, but are most fully described and illustrated in my copending application Serial No. 98,514, filed August 29, 1936, of which this application is a division.

It will be understood that the above-described structure is merely illustrative of the manner in which the principles of my invention may be utilized and that I desire to comprehend within my invention such modifications as come within the scope of the claims and the invention.

Having thus fully described my invention, what I claim as new and desire to secure by Letters Patent is:

1. In a printing machine including stationary ink supply means, printing plate means, and reciprocatory carrier means cooperating therewith, an ink transfer unit in said carrier means including rotatable ink transfer roller means alternately engageable with said ink supply means and said printing plate means, and ink spreader means associated with said ink transfer means and means comprising a cam and associated roller mechanism responsive to reciprocation of said carrier to axially reciprocate said ink spreader for uniformly distributing ink on said ink transfer roller means.

2. In a printing machine including stationary ink supply means, printing plate means, and reciprocatory carrier means cooperating therewith, an ink transfer unit in said carrier means including resilient rotatable ink transfer roller means alternately engageable with said ink supply means and said printing plate means, and rigid ink spreader roller means associated with said ink transfer means and means comprising a cam and associated roller mechanism responsive to reciprocation of said carrier to axially reciprocate said ink spreader for uniformly distributing ink on said ink transfer roller means.

3. In a printing machine, a frame, a stationary printing plate in said frame, a carrier reciprocable in said frame adjacent said printing plate, ink transfer means on said carrier for applying ink to said printing plate, and means for supplying ink to said ink transfer means comprising a stationary ink container adjacent said printing plate, an ink supply roller rotatable in said container adapted to contact said ink transfer means, ink spreader means operatively associated with said ink transfer means for uniformly distributing ink thereover, and means responsive to reciprocation of said carrier for effecting controlled rotation of said ink supply roller including a roller on said carrier, a lever engaged by said roller during reciprocation of said carrier, and ratchet means connecting said lever with said supply roller.

4. In a printing machine, a frame, a substantially flat stationary printing plate in said frame, a carrier reciprocable in said frame adjacent said printing plate, ink transfer means on said carrier for applying ink to said printing plate, and means for supplying ink to said ink transfer means comprising a stationary ink container adjacent said printing plate, an ink supply roller rotatable in said container adapted to be contacted by said ink transfer means at intervals, means for spreading the ink uniformly over said ink transfer means, and means responsive to reciprocation of said carrier for effecting controlled rotation of said supply roller including a roller on said carrier, a lever swingably engaged by said roller during reciprocation of said carrier, and

ratchet means operatively connecting said lever with said supply roller.

5. In a printing machine, a frame, a substantially flat stationary printing plate in said frame, a carrier reciprocable in said frame adjacent said printing plate, ink transfer means on said carrier for applying ink to said printing plate, and means for supplying ink to said ink transfer means comprising a stationary ink container adjacent said printing plate, a supply roller rotatable in said container, means comprising an axial reciprocable roller for spreading the ink uniformly over said ink transfer means, and means for effecting controlled rotation of said supply roller including a roller on said carrier, a lever swingably engaged by said roller during reciprocation of said carrier, ratchet means operatively connecting said lever with said supply roller, and means for varying the initial position of said lever for controlling the rotation of said supply roller during each reciprocation of said carrier.

6. In a printing machine, a frame, a substantially flat stationary printing plate in said frame, a carrier reciprocable in said frame above said printing plate, ink transfer roller means on said carrier including resilient roller means for applying ink to said printing plate, and means for supplying ink to said ink transfer means comprising a stationary ink container adjacent said printing plate, a supply roller rotatable in said container which is adapted to contact said transfer roller means at intervals, means for spreading the ink uniformly over said ink transfer roller, and means responsive to reciprocation of said carrier for effecting controlled rotation of said supply roller and including a roller on said carrier, a lever swingably engaged by said roller, and ratchet means operatively connecting said lever with said supply roller.

7. In a printing machine, a frame, a substantially flat stationary printing plate in said frame, a carrier reciprocable in said frame above said printing plate, ink transfer means on said carrier including resilient roller means and associated axially reciprocable ink spreading means for applying ink to said printing plate, and means for supplying ink to said ink transfer means comprising a stationary ink container adjacent said printing plate, a supply roller rotatable in said container, ink spreader means associated with said ink transfer means and including a cam actuated mechanism responsive to reciprocation of said carrier to reciprocate said ink spreader, and cam actuated means responsive to reciprocation of said carrier for effecting controlled rotation of said supply roller and including a roller on said carrier, a lever swingably engaged by said roller during reciprocation of said carrier, ratchet means operatively connecting said lever with said supply roller, and means to control the rotation of said supply roller during each reciprocation of said carrier comprising a stop screw longitudinally adjustable in said frame and disposed in the path of said lever for limiting swinging movement thereof under the influence of said roller.

8. In a printing machine, stationary ink supply means including a lever controlled ink supply roller, a stationary printing plate adjacent said ink supply means, a carrier reciprocable in a path adjacent said ink supply means and above said printing plate, resilient ink transfer roller means on said carrier for alternately engaging said ink supply roller and said printing plate, rigid ink spreader roller means in said carrier operatively associated with said ink transfer

roller means, and cam actuated means responsive to reciprocation of said carrier for reciprocating said ink spreader roller means with respect to said ink transfer roller means.

9. In a printing machine, stationary ink supply means including a lever controlled ink supply roller, a stationary printing plate adjacent said ink supply means, a carrier oppositely reciprocable in a path adjacent said ink supply means and said printing plate, resilient ink transfer roller means on said carrier for alternately engaging said ink supply roller and said printing plate, rigid ink spreader roller means in said carrier operatively associated with said ink transfer roller means, and means responsive to reciprocation of said carrier for reciprocating said ink spreader roller means with respect to said ink transfer roller means, said last-named means comprising a stationary cam plate, a swingable roll reciprocating lever on said carrier, a roller on said lever engaging said cam plate, and means resiliently urging said roller against said cam plate.

10. In ink transfer means for a printing machine, a frame, a longitudinally reciprocable carrier mounted thereon, resilient ink transfer rollers disposed transversely in said carrier, an axially reciprocable ink spreader roller associated with said ink transfer rollers, and means coacting with a stationary means on said frame and responsive to longitudinal reciprocation of said carrier for reciprocating said ink spreader roller axially with respect to said ink transfer rollers.

11. In a printing machine having a stationary printing plate and ink transfer means mounted on a reciprocable carrier for applying ink to said printing plate; means comprising an ink fountain and an ink supply roller to supply ink to said ink transfer means for application to said printing plate, said ink supply roller being mounted for controlled rotation in said ink fountain and adapted to be engaged with said ink transfer means at intervals as the carrier is reciprocated, and means comprising a lever and ratchet operatively connected to said roller and actuated in response to reciprocation of said carrier for rotating said ink supply roller a predetermined amount during each operative cycle, said lever being provided with an adjusting screw whereby the lever can be set to increase or decrease the arc through which said ink supply roller is rotated during a printing operation cycle.

12. In a printing machine having a stationary substantially flat horizontal printing plate and ink transfer means mounted on a reciprocable carrier for applying ink to said printing plate; means comprising an ink fountain and an ink supply roller for supplying ink to said ink transfer means for application to said printing plate, an axially reciprocable ink spreader roller operatively connected with said ink transfer means, means comprising a cam actuated roller mechanism associated with said ink spreading roller to effect reciprocation thereof in contact with said ink transfer means when said carrier is reciprocated, said ink supply roller being mounted for controlled rotation in said ink fountain and engageable with said ink transfer means during each operative cycle, a lever and cooperating ratchet means operatively connected to said ink supply roller and responsive to reciprocation of said carrier for rotating said ink supply roller a predetermined amount during each operative cycle, and means for varying the rotary move-

ment of said ink supply roller for a printing operation cycle.

13. In a printing machine having a stationary substantially flat horizontal printing plate and ink transfer means mounted on a reciprocable carrier for applying ink to said printing plate; means comprising an ink fountain and an ink supply roller for supplying ink to said ink transfer means for application to said printing plate, said ink supply roller being mounted for controlled rotation in said ink fountain and engageable with said ink transfer means, means for distributing the ink uniformly on said ink transfer means, lever means operatively connected to said ink supply roller and responsive to reciprocation of said carrier for rotating said ink supply roller a predetermined amount during each operative cycle, and manually adjustable means for varying the amount of rotation of said ink supply roller in each operative cycle to control the supply of ink delivered to said ink transfer means.

14. In a printing machine having a stationary substantially flat horizontal printing plate and ink transfer means mounted on a movable carrier for applying ink to said printing plate; means comprising an ink fountain and an ink supply roller for supplying ink to said ink transfer means for application to said printing plate, ink spreader means operatively associated with said ink transfer means to uniformly distribute the ink over said ink transfer means, said ink supply roller being mounted for controlled rotation in said ink fountain and engageable with said ink transfer means at intervals during operation of said printing machine, lever means engageable with said carrier for movement thereby, ratchet means operatively connected to said lever and said ink supply roller, and means for manually adjusting the position of said lever for controlling the amount of rotation of said supply roller by said carrier during reciprocation thereof to control the supply of ink delivered by said ink supply roller to said ink transfer means.

15. In a printing machine, an ink fountain, printing plate means arranged adjacent and in substantial alignment with said ink fountain, common support means for said ink fountain and said printing plate means, carrier means reciprocable over and in contact with said ink fountain and said printing plate, ink supply means operable in said ink fountain providing the sole means for supplying ink to an ink transfer roller, ink transfer roller means carried by said carrier and alternately engageable with said ink supply means and said printing plate for transferring ink from said ink supply means to said printing plate and an ink spreader roller in operative engagement with said transfer roller providing the sole means for evenly distributing ink over said transfer roller after engagement with said ink supply means.

16. In a printing machine, an ink fountain, stationary substantially horizontal printing plate means adjacent said ink fountain, common support means for said ink fountain and said printing plate means, carrier means horizontally reciprocable over and in contact with said ink fountain and said printing plate means, ink roller supply means rotatable in said ink fountain providing the sole means for supplying ink to an ink transfer roller, and resilient ink transfer roller means on said carrier operatively associated with said ink roller supply means to pick up ink solely therefrom and alternately engageable with said ink roller supply means and said printing plate

for transferring ink directly from said ink supply roller to said printing plate during reciprocation of said carrier in one direction, an ink spreader roller in operative engagement with said transfer roller providing the sole means for evenly distributing ink over said transfer roller after engagement with said ink supply means, said transfer ink roller means being operable to engage said printing plate during reciprocation of said carrier in the opposite direction to uniformly distribute the ink on the surface of the printing plate, said ink spreader roller uniformly distributing the ink on the surface of the transfer roller during said last mentioned movement.

17. In a printing machine, an ink fountain, printing plate means arranged adjacent said ink fountain, common support means for said ink fountain and said printing plate means, carrier means reciprocable longitudinally of the machine and over said fountain and said printing plate, ink transfer roller means on said carrier, means comprising a cam and associated roller mechanism responsive to reciprocation of said carrier to dispense ink from said ink fountain onto said ink transfer roller means, ink spreader means axially reciprocable with respect to said ink transfer roller means for spreading the ink uniformly over the surfaces of said ink transfer roller means during reciprocation of said carrier means, means for axially reciprocating said spreader means comprising a cam plate extending longitudinally adjacent the path of reciprocation of said carrier, and means resiliently urging said spreader means in engagement with said cam plate whereby said spreader means is reciprocated axially upon longitudinal reciprocation of said carrier.

18. In a printing machine including a support, ink supply roller means on said support, type plate means on said support adjacent said ink supply means, carrier means reciprocable above said ink supply means and said type plate means, and ink transfer roller means coacting with an ink spreading roller on said carrier, said ink transfer roller means alternately engageable with a determined surface area of said ink supply roller means and with said type plate means, and means for adjusting the area of a new surface area exposed to said ink transfer roller, said ink spreading roller being reciprocable in response to reciprocation of said carrier to uniformly spread the ink on the surfaces of said ink transfer roller means.

19. In a printing machine including a support, a sole source of ink supply including a fountain and ink supply roller mounted on said support, type plate means on said support adjacent said ink supply means, carrier means reciprocable above said ink supply means and said type plate means, and resilient ink transfer roller means on said carrier alternately engageable with said ink supply roller means for picking up a determined quantity of ink from the sole source of supply and said type plate means during reciprocation of said carrier for transferring ink from said ink supply means to said type plate means, said ink transferring means comprising an ink spreading roller operatively associated with said ink transfer roller during reciprocation of said carrier, said ink spreader roller being axially reciprocable in response to the reciprocation of said carrier and providing the sole means for evenly distributing ink over said transfer roller.

20. In a printing machine including stationary

ink supply roller means, stationary printing plate means, and a common support therefor; a reciprocable ink transfer carrier unit alternately engageable with a determined surface area of said ink supply roller means and with said printing plate means for applying ink from said ink supply means to said printing plate means, means for adjusting the area of a new surface area exposed to said ink transfer roller, said unit including rotatable resilient ink transfer roller means and a rigid axially reciprocable ink spreader roller operatively associated with said ink transfer roller and arranged to be axially reciprocated by said carrier during its reciprocation, and means responsive to reciprocation of said carrier for reciprocating said ink spreader relative to said ink transfer roller for uniformly distributing ink on said transfer roller.

21. In a printing machine, a sole source of ink supply including an intermittently rotated ink supply roller, a stationary printing plate mounted on a common support and adjacent said ink supply means, a carrier mechanism longitudinally reciprocable in a path over and in contact with said ink supply means and said printing plate, resilient ink transfer roller means on said carrier for alternately engaging said sole source of ink supply and said printing plate, an ink spreader roller coacting with said ink transfer roller providing the sole means for distributing ink over said transfer roller, and means comprising a cam and associated roller mechanism responsive to reciprocation of said carrier to axially reciprocate said ink spreader to uniformly distribute ink on said ink transfer roller means.

22. In a printing machine, an ink fountain, printing plate means arranged adjacent said ink fountain, common support means for said ink fountain and said printing plate means, carrier means reciprocable longitudinally of the machine and over said fountain and said printing plate, ink transfer roller means on said carrier, means comprising a cam and associated roller mecha-

nism responsive to reciprocation of said carrier to dispense ink from said ink fountain onto said ink transfer roller means, ink spreader means axially reciprocable with respect to said ink transfer roller means for spreading the ink uniformly over the surfaces of said ink transfer roller means during reciprocation of said carrier means, means for axially reciprocating said spreader means comprising a stationary cam plate carried by said support means and extending longitudinally adjacent the path of reciprocation of said carrier, and means interconnecting said cam plate with said spreader means for axially reciprocating the same upon longitudinal reciprocation of said carrier.

23. In a printing machine, an ink fountain, printing plate means arranged adjacent said ink fountain, common support means for said ink fountain and said printing plate means, carrier means reciprocable longitudinally of the machine and over said fountain and said printing plate, ink transfer roller means on said carrier, means comprising a cam and associated roller mechanism responsive to reciprocation of said carrier to dispense ink from said ink fountain onto said ink transfer roller means, ink spreader means axially reciprocable with respect to said ink transfer roller means for spreading the ink uniformly over the surfaces of said ink transfer roller means during reciprocation of said carrier means, means for axially reciprocating said spreader means comprising a stationary cam plate carried by said support means and extending longitudinally adjacent the path of reciprocation of said carrier, lever means pivotally mounted upon said carrier interconnecting said spreader means with said cam plate, and means resiliently urging one end of said lever means in engagement with said cam plate whereby said spreader means is reciprocated axially upon longitudinal reciprocation of said carrier.

CLAYTON E. WYRICK.
